UNITED STATES PATENT OFFICE.

PATRICK B. DELANY, OF NEW YORK, ASSIGNOR TO HIMSELF, AND EDWARD A. CALAHAN, OF BROOKLYN, N. Y.

APPARATUS FOR SUBSTITUTING GAS FOR ELECTRIC LIGHTS.

SPECIFICATION forming part of Letters Patent No. 274,181, dated March 20, 1883.

Application filed August 21, 1882. (No model.)

To all whom it may concern:

Be it known that I, PATRICK B. DELANY, of the city and State of New York, have invented an Improvement in Automatic Apparatus for Substituting Gas for Electric Lights and the Reverse, of which the following is a specification.

In many places electric lamps are applied upon gas-fixtures, and in other instances buildings are provided with electric lights as well as with gas-lamps, in order that the gas may be used if any accident occurs to the lamps or dynamo-machines.

My present invention is for automatically turning on and igniting the gas in case of any interruption to the electric current passing to either arc or incandescent lamps, and for extinguishing the gas when the electric lights are re-established.

I make use of an electro-magnet in the circuit passing to the lamps, which magnet prevents the opening of the gas-cock so long as the current is in the circuit; but when the current is interrupted the gas is turned on automatically. I combine with the foregoing a device for igniting the gas-jets electrically, so that the turning on of the gas and its ignition automatically take place instantly if the electric lamps fail to act, and I furthermore provide for extinguishing the gas automatically when the electric lamps are again brought into action.

In the diagram I have introduced illustrative devices that show the features of my improvement; but I do not limit myself to the special appliances.

The dynamo-generator at A is to be of any desired character, and the lamps at B are to be either arc or incandescent.

The electro-magnet C is in the circuit to the lamps, and hence its armature D will be attracted so long as the circuit to the lamps is energized; but if a lamp-circuit is broken, or the dynamo stops generating, or the power ceases, the armature flies back. I make use of this movement of the armature for turning on the gas when the armature flies back, and for turning it off when the magnet is again energized.

Any suitable cock or valve may be employed for the aforesaid purpose—such, for instance,

as a cock revolved by a weight with one arm that is arrested by a projection on the armature-lever to hold the cock in a closed position. As the armature-lever flies back this arm is released and the weight turns the cock, opens the same, and another arm is arrested by the armature-lever and holds the cock open. When the magnet is again energized, the armature-stop draws away from this second arm and allows the weight to turn and close the flow of gas.

I have illustrated in the drawing a valve at h, that is pressed to its seat by the action of the magnet on the armature-lever D; but the valve is opened by the spring i as soon as the current ceases in the electro-magnet C.

Simultaneously with the turning on of the gas I bring into action gas-lighting sparks, so that the gas is ignited as soon as it reaches the burner. To effect this object any desired spark apparatus may be employed. I have shown a spring-barrel at l, with gearing to revolve the tooth-wheel m, that acts as a circuit-breaker with the contact-lever n and spring or spring-lever o, that are in an electric circuit to the primary of the induction-coil r. The secondary circuit passes to the burners s, where there are spark-points of ordinary character.

The circuit through the lever n and spring o may be from a battery, P, or from a storage-battery charged by the dynamo-generator; or the igniting-sparks may be produced in any other convenient manner.

A detent, R, on the armature-lever is employed for holding the spark apparatus out of action while the magnet C is energized, and for liberating the same and allowing the sparks to be developed as soon as the armature D flies back.

By this invention I am able to light up streets or public or private buildings by gas automatically, when the electric light fails or is purposely extinguished, and to extinguish the gas automatically as soon as the electric lights are restored.

I claim as my invention—
1. The combination, with the electric lamps, circuit and generating device, of an electro-magnet in the circuit to the lamps, a cock or valve controlled by the said electro-magnet,

gas-pipes and burners, spark-points at the burners, and electric appliances for sending a current to the spark-points, substantially as set forth.

5 2. The combination, with the gas-pipes and burners, of a cock or valve to open or close the gas-supply, an electro-magnet in an electric-lamp circuit, automatic mechanism to turn on and shut off the gas under the control of such electro-magnet, an induction-coil, appa-

ratus for pulsating the current in the primary of the induction-coil and spark-points, and a circuit connected with the secondary of such induction-coil, substantially as set forth.

Signed by me this 17th day of August, A.D. 15
1882.

PATRICK B. DELANY.
